UNITED STATES PATENT OFFICE

FRANK PALLONE, OF BROOKLYN, NEW YORK

DESIGN FOR A BASE FOR LAMP OR ANALOGOUS ARTICLES

Application filed May 12, 1931. Serial No. 39,816. Term of patent 7 years.

To all whom it may concern:

Be it known that I, FRANK PALLONE, a citizen of the United States, residing at Brooklyn, in the county of Kings and State of New York, have invented a new and original Design for Base for Lamp or Analogous Articles, of which the following is a specification, reference being had to the accompanying drawings, forming part thereof.

Fig. 1 is a front view of a base for lamp or similar articles showing my new design.

Fig. 2 is a side view thereof.

Fig. 3 is a diagrammatic plan view thereof.

I claim:

The ornamental design for a base for lamp or analogous articles, as shown.

FRANK PALLONE.
